**UNIT FOR SUPPORTING CONTAINERS STORING
FLUID MEDIUM UNDER PRESSURE**

Alfred F. Isnardi, Totowa, Steven J. Chup, Carlstadt, and William M. Weibel, Pompton Lakes, N.J., assignors to Specialties Development Corporation, Belleville, N.J., a corporation of New Jersey

Filed Apr. 18, 1962, Ser. No. 188,408

7 Claims. (Cl. 222—3)

The present invention relates to metallic receptacles, and, more particularly, to a unit including an improved arrangement of a plurality of spherical containers for storing fluid medium under pressure.

At present there is a need for a supply of hydrogen and oxygen which is utilized to operate various devices.

Accordingly, an object of the present invention is to provide a supporting unit including a container for confining gaseous hydrogen and a second container for confining gaseous oxygen.

Another object is to provide such a unit for confining these gases under extremely high pressures and thereby store a large supply of gas in a container having a small volume.

Another object is to provide such a unit which is compact, small in size and relatively light in weight but yet can store a desired quantity of the gaseous medium.

Another object is to provide such a unit which can be readily assembled.

A further object is to provide such a unit which is simple and economical in construction.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawings, forming a part of the specification, wherein:

FIG. 1 is a side view of a unit in accordance with the present invention with certain parts broken away for clearness.

FIG. 2 is a sectional view taken along the line 2—2 on FIG. 1.

FIG. 3 is a fragmentary bottom view illustrating a detail of the unit.

Referring now to the drawings in detail, there is shown a unit which generally comprises a spherical container 10 for storing oxygen having a valved outlet 11, a spherical container 12 for storing hydrogen having a valved outlet 13, and elements described hereinafter for maintaining the containers in side-by-side assembly with a longitudinally extending axis passing through the centers of the containers and with the outlets located in the space between adjacent surfaces of the containers and within the confines of the containers, that is, between the axis and the surface of the containers outermost of the axis.

The elements just mentioned include a chock 14 between the containers 10 and 12 having opposite surfaces 15 and 16 which are recessed at 17 or are otherwise contoured for receiving a portion of the containers 10 and 12 respectively; an end member 18 facing the surface 15 and contoured at 19 for receiving a portion of the container 10; an end member 20 facing the surface 16 and contoured at 21 for receiving a portion of the container 12; and a plurality of circumferentially spaced, lengthwise extending assembling means 22 connected between the end members 18 and 20 for relatively moving the end members towards each other to clamp and secure each container between its end member and the chock 14.

The assembling means 22 each include a strap 24 connected at one end to a lug 25 on the end member 20 and at the other end to a bolt 26 extending through an aperture 27 in the end member 18 and having a nut 28 threaded thereon which bears against a washer 29 at the outer face of the end member 18.

The valve controlled outlets 11 and 13 respectively include a valve 30, 31 and a conduit 32, 33 connected at one end to the outlet of the valve. The details of the valves 10 are not shown because these valves may be of any conventional type which are normally closed and are adapted to be respectively opened by a pull cable 34, 35.

The valves 30 and 31 face each other, with the longitudinal axis of the valve 30 on the container 10 being disposed in a horizontal plane and the longitudinal axis of the valve 31 on the container 12 being disposed in a vertical plane, as viewed in FIG. 1, so that these valves are spaced circumferentially about 90°. The valve 31 slants downwardly, and the valve 30 slants forwardly, both at an angle of about 45° to provide a compact arrangement.

As shown in FIG. 1, the valve 30 faces towards the right and its pull cable 34 extends horizontally through the end member 20; and the valve 31 faces towards the left and its pull cable 35 first extends horizontally towards the left, passes through a guide member, such as a U-shaped tube 36 secured to the inner face of the end member 18 to reverse its direction, and extends horizontally through the end member 20, whereby both pull cables are accessible at the outer face of the end member 20 and both pull cables are operable to open their valve by a pulling force from left to right.

The gases are stored in the containers at a high pressure but are used at a much lower pressure which is provided by conventional pressure regulators 37 and 38 for the containers 10 and 12, respectively. As shown in FIG. 2, the pressure regulators are mounted on the chock 14 and diverge upwardly therefrom at an angle of about 30° to the vertical.

In order to facilitate fluid flow connection of the pressure regulators to containers, the chock 14 has a pair of passageways 39 and 40 extending therethrough. The inlet of the pressure regulator 37 is connected to the upper end of the passageway 39, and the conduit 32 of the container 10 is connected to the lower end of the passageway 39. The inlet of the pressure regulator 38 is connected to the upper end of the passageway 40, and the conduit 33 of the container 12 is connected to the lower end of the passageway 40. The outlets of the pressure regulators each have a conduit 41 connected thereto which extends 50 through the end member 18.

The container 10 may be slightly smaller than the container 12, and is positioned by using an end member 18 which is a ring having a central opening providing the contour 19 for receiving the container 10. The end member 20 is circular plate formed with an inwardly facing recess which provides the contour 21 for receiving the container 12. The end members are of equal diameter and define a tubular envelope enclosing the containers, their valves, pressure regulators and pull cables, 55 and the assembling means, whereby a unit of minimum dimensions is provided.

In a practical embodiment of the present invention, the end members 18 and 20 have a diameter of about 4.75 inches and the overall length of the unit is about 8.5 inches. The container 10 is a steel sphere having an inner diameter of about 3.31 inches and having a wall thickness to safely store oxygen therein at 8000 p.s.i. The container 12 is a steel sphere having an inner diameter of about 4.13 inches and having a wall thickness to safely store hydrogen therein at 8000 p.s.i. The container 10 has a volume of about 19 cubic inches and the container 12 has a volume of about 37 cubic inches, whereby the

unit can store about 0.048 pound of hydrogen and about 0.533 pound of oxygen. The pressure regulators reduce the pressure of the gases to about 1.0 p.s.i. at the outlet thereof to provide a continuous flow of gases at such low pressure for about 48 hours. Such a unit weighs about 8 pounds when fully charged.

From the foregoing description, it will be seen that the present invention provides an improved arrangement of metallic receptacles for storing and supplying gases for power generating devices and the like.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

We claim:

1. A unit for supporting containers storing fluid medium under pressure, the unit comprising a pair of spherical containers for confining the medium therein and each having a valve controlled outlet, said containers being arranged side-by-side and with said outlets located in the space between adjacent surfaces of said containers, chock means between said containers having opposite surfaces each contoured for receiving a portion of one of said containers, an end member contoured for receiving a portion of one of said containers, an end member contoured for receiving a portion of the other of said containers, and means for relatively moving said end members towards each other to secure each of said containers between one of said end members and said chock means.

2. A unit for supporting containers storing fluid medium under pressure the unit comprising a pair of spherical containers for confining the medium therein and each having a valve controlled outlet, said containers being arranged side-by-side and with said outlets located entirely in the space between adjacent surfaces of said containers, chock means between said containers having opposite surfaces each contoured for receiving a portion of one of said containers, an end member contoured for receiving a portion of one of said containers, an end member contoured for receiving a portion of the other of said containers, means for relatively moving said end members towards each other to secure each of said containers between one of said end members and said chock means, and conduit means connected at one end to each of said container outlets and extending through said chock means.

3. A unit according to claim 2, wherein a pressure regulator is connected to the other end of each conduit means, and said pressure regulators are located substantially entirely in the space between adjacent surfaces of said containers.

4. A unit for supporting containers storing fluid medium

under pressure, the unit comprising a pair of spherical containers for confining the medium therein and each having a valve controlled outlet, said containers being arranged side-by-side and with said outlets located entirely in the space between adjacent surfaces of said containers, a chock member between said containers having opposite surfaces each contoured for receiving a portion of one of said containers, an end member contoured for receiving a portion of one of said containers, an end member contoured for receiving a portion of the other of said containers, means for relatively moving said end members towards each other to secure each of said containers between one of said end members and said chock member, said chock member having a pair of passageways extending therethrough, and a conduit member for connecting each of said container outlets to one end of one of said passageways.

5. A unit according to claim 4, including a pair of pressure regulators mounted on and secured to said chock member and located substantially entirely in the space between adjacent surfaces of said containers, each of said regulators having an inlet connected in fluid flow communication with the other end of one of said passageways.

6. A unit for supporting containers storing fluid medium under pressure, the unit comprising a pair of spherical containers for confining the medium therein and each having a valve controlled outlet, said containers being arranged side-by-side and with said outlets located entirely in the space between adjacent surfaces of said containers, a chock member between said containers having opposite surfaces each contoured for receiving a portion of one of said containers, an end member contoured for receiving a portion of one of said containers, an end member contoured for receiving a portion of the other of said containers, means for relatively moving said end members towards each other to secure each of said containers between one of said end members and said chock member, a pull cable for opening each of said valve controlled outlets, and guide means for said cables for rendering the end of said cables at which an operating force is to be applied accessible at the outer side of the same end member.

7. A unit according to claim 6, wherein said guide means include a guide element mounted on the inner side of said other end member for reversing the direction in which one of said cables is guided.
